(57) **CLAIM**

The ornamental design for an anti-theft cap for a medicine bottle, as shown.

DESCRIPTION

FIG. 1 is a front view of an anti-theft cap for a medicine bottle showing my new design; FIG. 2 is a rear view thereof; FIG. 3 is a left view thereof; FIG. 4 is a right view thereof; FIG. 5 is a top view thereof; FIG. 6 is a bottom view thereof; FIG. 7 is a perspective view thereof; and, FIG. 8 is another perspective view thereof shown in a position of use attached to a bottle drawn in broken lines. The dash-dash broken lines in FIG. 6 depict portions of the anti-theft cap for a medicine bottle that form no part of the claimed design. The dot-dot-dash broken lines in FIG. 8 illustrating a bottle depict environment and form no part of the claimed design.

1 Claim, 8 Drawing Sheets
